CREPING MACHINE

Louis A. Straubel and James W. Straubel, Green
Bay, Wis.; said Louis A. Straubel assignor to
said James W. Straubel, as trustee

Application November 27, 1944, Serial No. 565,208

8 Claims. (Cl. 154—30)

1

This invention relates to a creping machine for creping dry web material, such as paper and the like, to impart thereto a high degree of softness and stretchability.

It has heretofore been proposed to crepe web material, such as paper, in a dry state by means of a pair of doctor blades ground to conform to the curvature of the creping rolls and provided with sharp leading edges held in tight surface contact with the surfaces of the rolls. For various reasons, such prior art devices have proved unsatisfactory for the commercial production of creped paper. For one thing, the sharp edges of the doctor blades tend to tear the paper web, especially when light paper is being creped. Particles of dirt, grit or the like frequently become wedged between the sharp doctor blade edges and the surfaces of the rolls and either tear or weaken the paper as it passes thereagainst.

In accordance with the principles of our invention creping plates are provided having relatively blunt, or rounded, leading edges. Preferably, the rounded leading edges are held in closely spaced relation to the surfaces of the creping rolls, rather than in tight pressure relationship as heretofore. The creping plates need not be ground to conform with the curvature of the creping rolls, but should merely be sufficiently relieved to permit the leading edges to extend into closely spaced relationship with the bite of the rolls. Under these circumstances, a dry web of paper can be satisfactorily creped to give a high degree of softness and stretchability, and eliminate the danger of tearing the web during the creping operation.

It is therefore an important object of our invention to provide a creping machine for the creping of web material, such as paper and the like, in a dry state, the machine being provided with creping plates having blunt, or rounded, leading edges that extend into the delivery side of the bite of the creping rolls but are preferably slightly spaced from the roll surfaces or at least not in pressure contact therewith.

It is a further important object of this invention to provide a creping machine for the creping of dry web material, such as paper, using creping plates having blunt, or rounded, leading edges spaced slightly apart to provide a restricted passage between the creping plates, the blunt leading edges in cooperation with the surfaces of the creping rolls adjacent the bite therebetween serving to upset the web substantially at the bite itself and to cause the upset paper to accumulate in bunched condition between said creping plates.

It is a further important object of this inven-

2

tion to provide a creping machine including creping plates having blunt, or rounded, leading edges and providing a restricted passage for the accumulation of the bunched creped paper, and including evening rolls driven at a much slower rate of speed than the creping rolls for insuring a uniform and even distribution of the creped paper from such accumulation within or between the creping plates.

Other and further important objects of this invention will be apparent from the disclosures in the specification and the accompanying drawing.

On the drawing:

- 15 Figure 1 is a longitudinal sectional view of a creping machine embodying our invention.
Figure 2 is an end elevational view with the creping rolls removed.
Figure 3 is an enlarged, fragmentary view illustrating the arrangement of creping rolls and doctor plates.

The reference numeral 10 indicates a supply roll of web material mounted upon a stand 11 and provided with the usual braking means (not shown) for securing the proper tension on the web 12 as it is unwound from roll. A pair of feeding and creping rolls 13 and 14 are mounted in a pair of stands 15 with their axes in vertical alignment. Said rolls 13 and 14 are provided with hard smooth surfaces, preferably of chilled steel, to prevent scoring of the rolls by the paper in the creping operation. The ends of the shaft 16 of the upper roll 13 are journaled in a bearing block 17 that is vertically adjustable between the upright guides 18 of said stand 15. A bolt 19 threaded through the cross piece 20 at each end of the guide stands 18 serves to adjust the pressure between said feed rolls 13 and 14 at the bite 39 therebetween.

40 A pair of evening rolls 21 and 22 are mounted in a stand 23 behind the feeding and creping rolls 13 and 14 and with the bite between said evening rolls in horizontal alignment with the bite between the feeding and creping rolls 13 and 14.

45 Said evening rolls 21 and 22 are so arranged that they are not in contact with each other but their surfaces are spaced slightly apart to provide for the passage therebetween of the creped paper, indicated by the reference numeral 12a. The surfaces of said rolls 21 and 22 may suitably be knurled, as indicated at K, although they may also be smooth.

50 Between the sets of feeding and creping rolls and evening rolls there is mounted a pair of rigid creping plates 24 and 25. Said plates extend the full width of the rolls and are supported so as to be adjustable relative to each other to provide a

gap 26 therebetween. For this purpose, the creping plates 24 and 25 may be suitably carried by sets of straps 27, 27 and 28, 28 from the roll supporting stand 23, the straps being slotted and provided with bolts 29 and 30 for securing said straps to said supporting stand 23. Adjustment of the width of the gap 26 between said creping plates 24 and 25 may be performed by loosening the bolts 29 and 30 and moving the plates toward or away from each other.

The creping plates 24 and 25, as best shown in Figure 3, comprise a pair of rigid plates having plane opposed surfaces 31 and 32, respectively, which are equally spaced from a plane tangent to said bite 39 between the feeding and creping rolls 13 and 14. Said surfaces 31 and 32 together form the restricted passage 26. The leading edges 33 and 34 of said creping plates 24 and 25 are rounded upon a radius that may vary between $\frac{1}{16}$ and $\frac{1}{4}$ of an inch. Rearwardly of said leading edges 33 and 34, the creping plates are relieved, as at 35 and 36, respectively, to provide clearance between the plates and the surfaces of the rolls 13 and 14. The creping plates are similarly relieved at their rear edges, as at 37 and 38 for clearance with the surfaces of the evening rolls 21 and 22. It will be noted that said leading edges 33 and 34 extend into close proximity with the bite, indicated at 39, between said rolls 13 and 14 and into closely spaced relationship with the surfaces of said rolls, but preferably not in actual contact therewith.

A pair of draw rolls 40 and 41 are mounted behind the evening rolls in vertical pressure relationship to each other upon a stand 42. The upper roll 40, like the roll 13, has a shaft 43 that is journaled at its ends in bearing blocks 44 that are vertically adjustable between the upright guides of said stand 42, as by means of a pair of bolts 45. The rolls 40 and 41 are preferably provided with a soft or yielding surface, such as rubber or felt, so as not to calender out the crepe that is put into the web 12a. The speed of the draw rolls 40 and 41 can be regulated to leave any percentage of crepe desired in the paper, or if the surface speed of the rolls 40 and 41 is the same as that of rolls 13 and 14, they will tend to pull out most of the crepe but will nevertheless leave the paper considerably softer. From the draw rolls 40 and 41 the web 12a is rewound into a roll 47.

The lower feed roll 14 may suitably be driven by means of a belt 48 passing around a pulley 49 that is keyed to the roll shaft 50. The upper feed roll 13 is driven through a pair of meshing pinion gears 51 and 52 secured to said shafts 50 and 46, respectively. This insures the rolls 13 and 14 being driven at the same rate of surface speed.

The evening rolls 21 and 22 may be geared together by pinions 53 and 57, but are independently driven by any suitable means (not shown) at a greatly reduced surface speed with respect to said feed rolls, as for instance in the ratio of 1 to 35. These rolls regulate the rate of discharge of the bundles of creped paper from the accumulation 65. The reduced speed of the rolls is necessary because the creped paper is in bundles as it passes through the evening rolls. These rolls thus also serve to put back pressure on the paper to cause it to be upset back in the bite of the rolls 13 and 14.

The shaft 50 also carries a sprocket gear 53 around which is trained a chain 54 for driving a sprocket gear 55 secured to the shaft 56 of the lower draw roll 41. The upper draw roll 40 is

driven through intermeshing pinions 62 and 61 secured to the shaft 56 and the upper shaft 43, respectively, so that the draw rolls will be driven at the same surface speed. The surface speed of the draw rolls 40 and 41 is preferably slightly less than that of the feed rolls 13 and 14.

The operation of the machine of our invention is as follows:

In starting up the machine, the leading end of the web 12 is fed into the bite 39 between the feeding and creping rolls 13 and 14. The web tends to pass in a straight line between said rolls and not to adhere to either of them. As the web passes into the restricted passage 26 between the creping plates, the friction of the web upon the plane surfaces 31 and 32, as well as the slower moving surfaces of the evening rolls 21 and 22, causes the paper to back up and fold upon itself until an accumulation of bunched-up paper, as indicated at 65, is produced. The pressure placed upon the web ahead of the leading edges 33 and 34 causes the paper to be upset on the delivery side of the rolls 13 and 14 substantially back into the bite 39.

As the pressure of the paper in back of it forces the bunched-up accumulation 65 out of the passage 26, the creped paper 12a is caused to pass between the evening rolls 21 and 22, which serve to deliver the creped paper evenly and uniformly. The creped web 12a is then passed through the bite of the rolls 40 and 41, from which the creped web passes through the rewinder to be wound up into a roll 47. The pressure between the draw rolls 40 and 41 is controlled so that the resilient surfaces of these rolls will not take out too much of the crepe.

By virtue of the construction above described, the machine of our invention is capable of producing commercially a heavily creped web of paper, starting with the web in dry condition. As illustrative of some of the more important dimensions, the leading edges 33 and 34 may be set within $\frac{3}{4}$ and $1\frac{1}{4}$ inches from the bite 26. One of the leading edges may be slightly in advance of the other, or the two edges may be in vertical alignment. The restricted passage 26 may suitably be around $\frac{1}{4}$ of an inch in width, depending upon the basic weight of the paper being creped. The knurled evening rolls 21 and 22 may be spaced apart by as much as $\frac{1}{8}$ and $\frac{3}{8}$ of an inch.

It will, of course, be understood that various details of construction may be varied through a wide range without departing from the principles of this invention and it is, therefore, not the purpose to limit the patent granted hereon otherwise than necessitated by the scope of the appended claims.

What we claim is:

1. In a creping machine for paper and other web material, a pair of smooth surfaced rolls forming a bite therebetween into which said web is drawn, a pair of rigidly mounted creping plates providing a restricted passage therebetween and extending into the delivery side of said bite, said plates having blunt leading edges closely adjacent to but not in pressure scraping relationship with said roll surfaces, said blunt edges in cooperation with the walls of said restricted passage having the effect of backing said web up upon itself in said bite ahead of said leading edges to be there creped, and means for drawing said creped web through and out of said restricted passage at a rate of speed such as to cause said web to retain much of its crepe.

2. In a creping machine for paper and other web material, a pair of smooth surfaced rolls forming a bite therebetween into which said web is drawn, a pair of rigidly mounted creping plates providing a restricted passage therebetween and extending into the delivery side of said bite, said plates having blunt leading edges closely adjacent to but not in pressure scraping relationship with said roll surfaces, said blunt edges in cooperation with the walls of said restricted passage having the effect of backing said web up upon itself in said bite ahead of said leading edges to be there creped, means for drawing said creped web through and out of said restricted passage at a rate of speed such as to cause said web to retain much of its crepe and a pair of spaced evening rolls for insuring a uniform and even feed of creped paper from said creping plates to said drawing means.

3. In a creping machine for paper and other web material, a pair of smooth surfaced rolls forming a bite therebetween into which said web is drawn, a pair of rigidly mounted creping plates providing a restricted passage therebetween and extending into the delivery side of said bite, said plates having rounded leading edges closely adjacent to but not in pressure scraping relationship with said roll surfaces, said rounded edges in cooperation with the walls of said restricted passage having the effect of backing said web up upon itself in said bite ahead of said leading edges to be there creped, the creped web bunching up in said restricted passage to form an accumulation therein, a pair of knurled rolls having slightly spaced surfaces for receiving the web therebetween from said accumulation and feeding the web uniformly and evenly and means for drawing said creped web through and out of said restricted passage and between said knurled rolls at a rate of speed such as to cause said web to retain much of its crepe.

4. In a creping machine for the dry creping of paper and other web material, a pair of feeding and creping rolls having smooth hard surfaces providing a bite therebetween for receiving the web material, a pair of rigidly mounted creping plates having plane opposed surfaces providing a restricted passage therebetween, said plates having rounded leading edges positioned adjacent to said bite on the delivery side thereof and in closely adjacent relationship but not in pressure scraping relationship to said rolls, said rounded edges in combination with said opposed surfaces having the effect of backing said web up upon itself in said bite ahead of said leading edges to be there upset and creped, the creped web bunching up in said restricted passage to form an accumulation therein and a pair of spaced knurled rolls for controllably releasing said creped web from such accumulation.

5. In a creping machine for the dry creping of paper and other web material, a pair of feeding and creping rolls having smooth hard surfaces providing a bite therebetween for receiving the web material, a pair of rigidly mounted creping plates having plane opposed surfaces providing a restricted passage therebetween, said plates having rounded leading edges positioned adjacent to said bite on the delivery side thereof and in closely adjacent relationship but not in pressure scraping relationship to said rolls, said rounded edges in combination with said opposed surfaces having the effect of backing said web up upon itself in said bite ahead of said leading edges to be there upset and creped, the creped web

bunching up in said restricted passage to form an accumulation therein, means including knurled rolls for controllably releasing said creped web from such accumulation and a pair of resilient rolls for drawing said creped web from said accumulation and through said knurled rolls at a uniform rate of speed.

6. In a creping machine for the dry creping of paper and other web material, a pair of feeding and creping rolls having smooth hard surfaces providing a pressure bite therebetween for receiving the web material, a pair of rigid creping plates having opposed plane surfaces equally spaced from a plane tangent to said roll surfaces at said bite, said plates having rounded leading edges positioned adjacent to said bite on the delivery side thereof, means for adjustably supporting said plates in fixed adjusted position to provide a restricted gap between said opposed surfaces, said rounded leading edges in combination with said opposed plane surfaces having the effect of backing up said web upon itself in said bite ahead of said leading edges to be there upset and creped, the creped web bunching up in said restricted passage to form an accumulation therein.

7. In a creping machine for the dry creping of paper and other web material, a pair of feeding and creping rolls having smooth hard surfaces providing a pressure bite therebetween for receiving the web material, a pair of rigid creping plates having opposed plane surfaces equally spaced from a plane tangent to said roll surfaces at said bite, said plates having rounded leading edges positioned adjacent to said bite on the delivery side thereof, means for adjustably supporting said plates in fixed adjusted position to provide a restricted gap between said opposed surfaces, said rounded leading edges in combination with said opposed plane surfaces having the effect of backing up said web upon itself in said bite ahead of said leading edges to be there upset and creped, the creped web bunching up in said restricted passage to form an accumulation therein, and a pair of spaced rough surfaced rolls driven at a much slower rate of speed than said feeding and creping rolls to aid in the uniform delivery of the creped web material from said accumulation.

8. In a creping machine for the dry creping of paper and other web material, a pair of feeding and creping rolls having smooth hard surfaces providing a pressure bite therebetween for receiving the web material, a pair of rigid creping plates having opposed plane surfaces equally spaced from a plane tangent to said roll surfaces at said bite, said plates having rounded leading edges positioned adjacent to said bite on the delivery side thereof, means for adjustably supporting said plates in fixed adjusted position to provide a restricted gap between said opposed surfaces, said rounded leading edges in combination with said opposed plane surfaces having the effect of backing up said web upon itself in said bite ahead of said leading edges to be there upset and creped, the creped web bunching up in said restricted passage to form an accumulation therein, a pair of spaced rough surfaced rolls driven at a much slower rate of speed than said feeding and creping rolls to aid in the uniform delivery of the creped web material from said accumulation and a pair of resilient surface rolls for drawing said creped web through said rough surfaced rolls.
